APPARATUS FOR SAMPLING LIQUIDS

Emerson W. Pribble, Oklahoma City, Okla.

Application August 7, 1933, Serial No. 683,937

4 Claims. (Cl. 137—18)

My invention relates to apparatus for taking samples of liquid from tanks or reservoirs, and more particularly for use in sampling liquids which have a tendency to stratify when left for a time in an inert condition.

When crude oil is placed in tanks for storage and left for any considerable time, the extraneous matter such as sand or shale settles to the bottom of the tank along with the heaviest portion of the oil. These settling are known as "basic sediment" and is commonly referred to in the art as "B. S.", and consists usually of a layer of the sand or shale impregnated with the heaviest portion of the oil. Above the "B. S." the oil in the tank will graduate upwardly to the top where the lightest portions will occur. In taking samples from a tank of oil it is therefore necessary to procure a sample from various heights in the tank and to then mix them in order to obtain an average sample of the oil. The apparatus now used for taking such samples is commonly known in the art as an "oil thief" and usually consists of an open bottomed vessel adapted to be lowered upon a line into the tank and having a bottom closure operated from above the tank for closing the vessel and trapping the oil.

This type of apparatus has proven unsatisfactory due to the fact that it is necessary for the operator to guess at what height in the tank the various samples are taken. The samples are therefore usually taken at irregular heights in the tank and therefore do not correctly represent a true status of the sample of the oil when they are mixed.

Another type of "oil thief" also has a mechanical arrangement for operating the closure when the vessel contacts the bottom of the tank, or in its being lowered, meets the stratum of "B. S.". This type is impractical because the closure is in many instances prevented from functioning due to contact with the sand or shale in the "B. S."

The prime object of my invention is to provide a device of the class described which will be automatically operated to take the samples at various pre-determined heights in the tank.

Other objects of my invention are to provide a device of this class which is new, novel, practical and of utility; which will be positive in action; which will prevent the closure from being intercepted in its operation by contact with the "B. S."; which will make it possible to obtain a true representative sample of a tank of oil; which will embody a positive means for opening the closure without damage to the operating mechanism; which will be durable; which will be compara-

tively cheap to manufacture; the operating mechanism of which may be installed as an accessory upon "oil thieves" now in use, or may be built as a "factory job" upon new equipment; and, which will be efficient in accomplishing all the purposes for which it is intended.

With these and other objects in view as will more fully appear, my invention consists in the construction, novel features, and combination of parts hereinafter more fully described, pointed out in the claims hereto appended, and illustrated in the accompanying two-sheet drawing, of which,

Figure 1 is a side elevational view of the device;

Fig. 2 is a front elevation;

Fig. 3 is a detail of the closure releasing mechanism; and,

Fig. 4 is a detail of the extension mechanism to be used in connection with the trip-rod shown in Figs. 1 and 2.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawings are to be interpreted as being illustrative and not restrictive.

One practical embodiment of the invention as illustrated in the accompanying drawings comprises a preferably square elongated vessel 1 having an open bottom 2 and preferably having an entirely open top 3. The vessel is bounded by a front 4, a back 5, and two sides 6 and 7. Pivotally mounted in the sides 6 and 7 and spanning the top 3 is a bail 8 of any desired configuration. The bail is adapted to receive a cable or other supporting means for lowering the vessel into a body of liquid. Rigidly attached by screws 9 to the sides 6 and 7 adjacent the bottom 2 is provided a base-bracket 10 which projects outwardly past the front 4 and which at each side is provided with a brace 11.

The base-bracket 10 acts as a guide for a closure or gate 12 which is adapted to slide in grooves, not shown, carried by the inner surfaces of the walls of the vessel, when the closure is at its outer end of its throw. The front end of the closure is provided with two spaced upstanding projections 13 between which extends a pin 14. Rigidly attached to the front 4 adjacent the upper

portion of the vessel is a flat tapered spring 15 the lower end of which passes between the body of the closure and the pin 14 and is then turned upwardly. The spring is thus prevented from 5 becoming disengaged from the closure. Said spring 15 is provided for the purpose of urging the gate 12 to a closed position. A lever 16 is pivotally mounted upon the front 4 by a fulcrum 17 at a point slightly above the closure and the 10 lower end of the lever is adapted to contact the closure in such a manner that when its upper end is forced manually toward the front 4 the closure will be partially withdrawn from its closed position. A coil spring 18 is provided between the 15 lever and the front 4 for normally holding the upper end of the lever at the end of its throw away from the front 4.

The sides 6 and 7 are each provided with rigidly mounted bearing members 19, 20, 21, and 22, 20 respectively. Slidably mounted in the bearings is provided a trip-rod 23 which has its central portion bent at an angle forward and the front portion of which extends across the front 4. The front 4 is provided with a stop 24 which limits 25 the upward movement of the trip-rod.

Around the rod 23 and between the bearings 19 and 20 and between the bearings 21 and 22 are provided respectively two sleeves 25 and 26 which are each normally held against the respective 30 bearings 20 and 22 by coil springs 27. One of the sleeves is provided with a set screw 28 whereby it may be connected firmly to the rod at any desired point intermediate its top and bottom. Rigidly mounted between the sleeves 25 and 26 35 and extending outwardly past the front 4 is a bracket 29 the lower end of which is positioned adjacent the outer end of the gate 12 when the gate is at the outer end of its throw. The bracket 29 is adapted to engage the lower up-turned end 40 30 of the spring 15 to hold the spring in a set position and to thus hold the gate at the outer end of its throw.

A scale 31 of inches is provided upon the front 4 or upon the side 6 in order to indicate the distance below the bottom of the vessel at which the rod 23 is set.

In operation, if it is desired to take a sample of fluid three inches above the bottom of a tank, the set screw 28 will be loosened and the rod will 50 be moved downwardly until its uppermost portion is even with the three inch mark on the scale 31. The set screw will then be tightened and the closure 12 will be pulled outwardly thus bringing the lower end of the spring into hooked engagement with the bracket 29. The rod 23 will have to be raised slightly in order to let the end 55 of the spring pass beneath the bracket 29. The device is then in position to be lowered into the tank. When the device is lowered into the tank 60 upon the aforesaid cable, the ends of the rod 23 will pass through the bottom sediment and strike the bottom of the tank. The weight of the vessel will compress the springs 27 sufficiently to 65 disengage the spring 15 from the bracket 29 and the spring will instantly force the closure 12 into a closed position.

Since the vessel during the lowering operation has had both its top and bottom open it will have been lowered through the liquid without carrying any of the liquid downwardly with it, and therefore when the closure is closed the sample will be taken at the point at which the vessel is situated. The closure 12 is preferably slightly

wedge-shaped longitudinally and consequently will make a fluid tight seal with the hereinabove described grooves on the inner walls of the vessel which grooves are also tapered.

In Fig. 4 is illustrated an extension which may be used upon either or both ends of the rod 23. This extension consists substantially of a tube 32 adapted to pass over the end of the rod 23 and having a set screw 33 in its upper end for attaching it firmly to the rod. The lower end of the 10 tube 32 is also provided with a similar set screw 34 whereby a second rod 35 may be firmly attached within the lower end of the tube. The tube 32 and the rod 35 may be of any desired 15 length so that samples may be taken at any desired height above the bottom of a tank.

Obviously, the invention is susceptible of embodiment in forms other than that which is illustrated in the accompanying drawings and described herein, and applicable, for uses and 20 purposes other than as detailed, and I therefore consider as my own all such modifications and adaptations and other uses of the form of the device herein described as fairly fall within the 25 scope of my invention.

Having thus described my invention, what is claimed and desired to be secured by Letters Patent, is:

1. In a device of the class described, the combination with a body having open ends, and a 30 slidable closure for the lower end thereof, of a spring carried by the exterior of the body and connected to the closure for urging it to a closing position, longitudinally movable rods carried by opposite sides of the body and adapted to extend below the bottom thereof, said rods connected together for simultaneous movement, and a latch for holding the closure in an open position, said latch slidably carried by the rods and adapted to be 35 adjustably connected thereto for movement therewith, and adapted to release said closure to the action of said spring when the rods are moved upwardly with relation to the body.

2. Organization as described in claim 1, and 40 spring means for sufficiently retarding upward movement of the rods with relation to the body to cause the rods to penetrate through bottom sediment before they are moved.

3. In a device of the class described, the combination with a body having open ends, and a 45 slidable closure for the lower end thereof, of a spring carried by the exterior of the body and connected to the closure for urging it to a closing position, longitudinally movable rods carried by opposite sides of the body and adapted to extend below the bottom thereof, said rods connected together 50 for simultaneous movement, a latch for holding the closure in an open position, said latch slidably carried by the rods and adapted to be adjustably connected thereto for movement therewith, and adapted to release said closure to the action 55 of said spring when the rods are moved upwardly with relation to the body, a fulcrum carried by the body, and a pry-bar mounted upon the fulcrum for urging the closure toward an open position.

4. Organization as described in claim 3, and 60 spring means for sufficiently retarding upward movement of the rods with relation to the body to cause the rods to penetrate through bottom sediment before they are moved.
